BY Irving F. Goodfriend

UNITED STATES PATENT OFFICE

133,922

DESIGN FOR A PIN OR SIMILAR ARTICLE

Fred L. Landsberg, New York, N. Y.

Application January 26, 1942, Serial No. 105,436

Term of patent 3½ years

To all whom it may concern:

Be it known that I, Fred L. Landsberg, a citizen of the United States and resident of the county of Kings, City and State of New York, have invented a new, original, and ornamental Design for a Pin or Similar Article, of which the following is a specification, reference being had to the accompanying drawing, forming a part thereof and in which

I claim:

The ornamental design for a pin or similar article, substantially as shown.

FRED L. LANDSBERG.
